PACKAGE FILLING MACHINE

Charles Doering, Henry H. Doering, Bert J. Skoglund, and Eric W. Anderson, Chicago, Ill.; said Skoglund and said Anderson assigns to Charles Doering and Henry H. Doering, both of Chicago, Ill.

Application March 18, 1940, Serial No. 324,460

20 Claims. (Cl. 226—107)

This invention relates to receptacle filling machines and more particularly to combined measuring and container filling machines for viscous substances, although certain features thereof may be employed with equal advantage for other purposes.

It contemplates more especially the provision of improved means for filling packages with viscous substances such as pasteurized cheese, freshly churned butter, bread spreads, shortening compositions and similar plastic substances to effect the confinement of pre-measured amounts in containers with utmost sanitation and without entailing much time, labor or expense.

Heretofore it has been the practice to largely depend upon hand filling of boxes or other containers with plastic substances such as freshly pasteurized cheese and similar edible substances. This involves appreciable manual labor, time, and is not conducive to the desired sanitation which is a requisite with edible products. While machines have heretofore been proposed for filling packages with plastic substances, yet these have not proven entirely satisfactory for the purpose in that viscous substances are rendered more dense responsive to pressure and are otherwise impaired both from an appearance as well as texture standpoint when subjected to handling in a manner that is not conducive to uniform or sanitary treatment.

It is imperative, therefore, that edible substances such as butter, lard, cheese, oleomargarine, shortening compositions, and similar plastics be subjected to uniform handling in order to control their density and to avoid any impairment to the homogeneity of the constituent substances throughout their mass during the filling of containers with premeasured quantities thereof. Plastic substances of this character readily change in density, moisture content, homogeneity and texture when subjected to even slight variations in pressure and handling during packaging so that the resultant packaged product is not entirely satisfactory nor uniform in packed weight or appearance unless these variables are eliminated during packaging.

One object of the present invention is to simplify the construction and improve the operation of machines of the character mentioned.

Another object is to provide improved means for effecting the premeasured filling of boxes or other receptacles with viscous substances to effect the confinement thereof with utmost sanitation and without entailing any appreciable time or labor.

Still another object is to provide improved combined means for filling receptacles with premeasured quantities of viscous substances to confine such with uniform density and without impairment to the composition thereof.

A further object is to provide improved combined means for filling receptacles with premeasured quantities of edible viscous substances at a predetermined density without requiring skilled 10 supervision, handling, or entailing much time.

A still further object is to provide a carton filling device that discharges edible viscous substances in premeasured quantities within the confines of containers at a predetermined density and 15 without impairment to the texture thereof.

Still a further object is to provide automatic means for filling receptacles with plastic substances with the utmost sanitation, uniformity in texture, and in predetermined quantities so that 20 the successive receptacles will be uniform, slightly in appearance and completely sanitary.

Other objects and advantages will appear from the following description of an illustrative embodiment of the present invention.

25 Figure 1 is an enlarged plan view of a machine embodying features of the present invention.

Figure 2 is an enlarged front side view in elevation of the machine shown in Figure 1.

Figure 3 is a sectional plan view through the 30 main feeding piston and secondary control piston substantially along line III—III of Figure 2.

Figure 4 is a sectional view of a control ratchet taken substantially along line IV—IV of Figure 1.

Figure 5 is a rear side view in elevation of the 35 machine shown in Figures 1 and 2.

Figure 6 is an enlarged end view in elevation of the machine shown in Figures 1, 2 and 5.

mechanism taken substantially along line XIII—XIII of Figure 5.

Figure 14 is a detail view of the cylinder adjustment stop for the primary piston shown in Figures 2 and 5.

Figure 15 is a perspective view of the discharge valve element.

Figure 16 is a fragmentary side view in elevation of one end of the control piston showing the cap attachment therefor.

Figure 17 is a sectional view of a cam element taken substantially along line XVII—XVII of Figure 6.

Figure 18 is a sectional view of the package conveyor taken substantially along line XVIII—XVIII of Figure 2.

The structure selected for illustration comprises a frame 10 constructed from any suitable material such as angle iron to present a substantially rectangular unit supported at the desired elevation by forward and rearward corner standards 11 and 12. The frame 10 supports, in this instance, a secondary frame 17 in superposed relation therewith. To this end, forward and rearward corner super-standards 18 and 19 extend upwardly from the frame 10 to sustain the secondary frame 17 with its flat top surface 20 in a horizontal plane parallel to the frame 10 for mounting instrumentalities to be hereinafter described. A pair of confronting angle bars 21 and 22 serving as guide rails are horizontally disposed in adjustable spaced relation beneath the flat top surface 20, and each are provided with upwardly inclined extensions 23 and 24, respectively, that serve as gravity feed rails for containers, boxes or receptacles 25 which slide down to the horizontal guide rails 21—22.

The latter rails 21—22 are spaced to receive an endless conveyor belt 26 therebetween, the conveyor belt 26 extending between end rollers 27 and 28 mounted on shafts 29—30 journalled in bearing brackets 31 and 32, respectively. The bearing brackets 31—32 are bolted or otherwise secured to the frame 10 to support the rollers 27—28 with their endless conveyor belt 26 in the plane of the guide rails 21—22 to urge the boxes 25 forwardly. As shown, the horizontal guide rails 21—22 are mounted on lugs 33—34 (Figure 11) that have oppositely threaded and aligned bores 35—36 to receive correspondingly threaded rods 37 and 38 therethrough (Figure 2) for effecting the approach and separation of the guide rails 21—22.

A crank 39 is fixed to the rod 37 to impart rotation thereto so that the rails 21—22 may be adjustably spaced relative to the conveyor 26 to accommodate boxes 25 of varying length. So that the guide rails 21—22 will be uniformly spaced by imparting corresponding rotation to the corresponding rods 37—38 responsive to the crank 39, the rod 38 is provided with a sprocket wheel 41 beyond the standard 19 on the extremity opposite to the mounted crank 39. Another sprocket wheel 40 is fixed to the extending extremity of the rod 37 (Figure 11) to receive a sprocket chain 42 in meshing engagement with the sprocket wheels 40—41 so that rotation of the crank arm 39 will cause the rails 21—22 to approach or separate along the latter's full length. The inclined extension rails 23—24 are correspondingly adjusted by means of one or more oppositely threaded studs 42' (Figure 1) that are in threaded engagement therewith for manipulation independent of the crank 39.

It is to be noted that tension adjusting bolts 43

are provided on the forward bearing brackets 31 to maintain the conveyor belt 26 at the proper tension and compensate for stretch therein. The conveyor belt 26 is appreciably narrower than the normal separation of the guide rails 21—22 (Figure 11) so that containers of different lengths can be supported therein. This permits the feeding of the receptacles or containers 25 of varying length on the conveyor 26 in predetermined timed relation with the feeding mechanism in that the timing is responsive to the filling of the container which is controlled by the adjustments in the feeding cylinder as will appear more fully hereinafter. So that the foremost receptacle or container 25 will be held stationary in predetermined filling position relative to the moving belt 26 which frictionally glides thereunder, an indexing mechanism 44 is disposed in substantially vertical alignment with the foremost receptacle or container 25.

The indexing mechanism 44 comprises, in this instance, a pair of confronting brackets 45 and 46 mounted on the frame 10 by means of threaded studs 41. The brackets 45—46 support a stud shaft 48 that is journalled therebetween to rotatively support a cylindrical member 49 having end plates 50 and 51 through which the stud shaft 48 projects. As shown, the end plates 50—51 are provided with a plurality of circumferentially spaced teeth 52—53 that are disposed in the path of the foremost receptacle or container 25 to serve as a stop therefor. The teeth 52—53 serve to present a stop to the foremost container or receptacle 25 which is held in vertical registry with the filling mechanism as will appear more fully hereinafter.

In order that the indexing mechanism 44 may be synchronized with the feeding mechanism, a toothed plate 54 is mounted on the stud shaft 48 proximate to the bracket 46 (Figure 18). The toothed plate 54 is comparatively smaller than the end plates 50—51 and is provided with a plurality of circumferentially spaced teeth 55 disposed oppositely to the teeth 52—53 of the plates 50 and 51. The bracket plate 46 is provided with an offset upward extension 56 which is apertured as at 57 in alignment with the teeth 55 on the plate 54 to guide a vertical rod 58 that is reciprocally mounted therein.

The reciprocally mounted rod 58 is elevated by a suitable timing mechanism to be hereinafter described to permit the cylindrical member 49 to rotate responsive to the friction imparted thereto by the endless conveyor belt 26. The surface of the cylindrical member 49 is serrated or suitably knurled to provide a roughened surface confronting the underside of the conveyor belt 26 so that there will be no idling or free slippage of the member 49 relative to the belt 26 unless the rod or indexing trip 58 is in its extreme downward position in engagement with one of the teeth 55 on the plate 54. Whenever the vertical trip 58 is elevated, the cylindrical member 49 is rotated responsive to the friction imparted thereto by the linear movement of the conveyor belt 26 so that the foremost receptacle or container 25 may be carried away with the belt 26 after being filled with a premeasured quantity of contents.

The substance with which the box or container 25 is to be filled is received, in this instance, by a suitable cylindrical feeding housing communicating with a suitable source of substance supply such as a processing machine for conversion into the desired commodity possessed of the proper characteristics. In the case of cheese, a feeding

housing 59 will communicate with the pasteurization chamber of a machine to which the hopper 59 is connected in any suitable manner (not shown) for communication therewith. The housing 59 is provided, in this instance, with a helical feeding worm 60 whose housing and bearing bracket 61 receives the worm shaft 62 journaled therethrough for rotary support. The worm shaft 62 supports a sprocket wheel 63 for rotation therewith. To this end, the worm shaft 62 projects from the housing 59 so that the sprocket wheel 63 is externally carried thereon for rotation therewith.

As shown, the feeding housing 59 is supported around the peripheral edge thereof proximate to the bearing bracket 61 by means of a flanged circular bracket 64 which embraces the feeding housing 59. The supporting bracket 64 is supplied with flanges 65 to enable attachment to a cross beam 66 fixed to the underside of the super frame 11. The feeding housing 59 is provided with a rectangular orifice 67 that communicates with an orifice 68 provided in the supporting bracket 64 that is flanged as at 69 to present spaced confronting vertical mounts 70 provided with vertical guide grooves 70'.

A vertical measuring and dispensing cylinder 71 has a flat wall plate 71' reciprocally mounted and guided in the confronting grooves 70' of the supporting bracket 64 for registry of its intake orifice 72 with the orifices 67-68 of the feeding housing 59. The measuring and dispensing cylinder 71 has its orifice 72 proximate to the lower end 73 thereof (Figure 8). A piston 74 is fixed to a piston rod 75 that is guided in an axial bore 76 provided in a top cover plate 77 serving as a complement of the vertical measuring and dispensing chamber 71. As shown, the lower extremity of the measuring and dispensing cylinder 71 is inclined inwardly as at 78 for a depth commensurate with the aligned orifices 67-68-72 to serve as a lower limit stop for the piston 74.

The upward limit stop for the piston 74 comprises a disc 79 that comprises part of an upwardly extending rod 80 which is threaded as at 81 for adjustable mounting in a cylindrical tubular member 82. The tubular member 82 projects through an upstanding boss 83 integrally or otherwise formed with the top closure plate 77 of the cylinder 71 to receive a threaded stud 84 therethrough. The threaded stud 84 engages the exterior surface of the tubular member 82 so that the latter may project into the measuring and dispensing cylinder 71 for any desired or adjusted distance.

Then, too, the limit rod 80 is threaded into the tubular member 82 and is provided with a lock nut 85 engaging the upper extremity thereof to maintain the threaded upper limit stop rod 80 in its desired position responsive to the rotation thereof in one direction or another by manipulating the knurled finger knob 86 fixed to the upper extremity thereof. It will be apparent, therefore, that a fine adjustment of the upper limit stop disc 79 may be effected through the medium of the threaded rod 80 and its lock nut 85 which retains the adjustment against accidental displacement.

In order to provide predetermined positions for the upper limit stop guide 82, a plurality of recesses 87 and 88, in this instance two, are provided in the exterior surface thereof (Figure 14) to receive the correspondingly shaped extremity of the threaded stud or set screw 84 so that two predetermined positions of the upward limit stop

79 may be predetermined without any extreme care for filling two different sizes of containers or receptacles 25. For instance, the lower recess 87 roughly determines the position of the upper limit stop 78 for a five pound content in containers 25, while the upper recess 88 will roughly determine the position thereof for a two pound content in containers 25. The accurate weight for this rough adjustment has been effected and is determined by the position of the upper limit stop rod 80 that has a fine adjusting thread 81 thereon to slightly vary the position one way or the other. Inaccuracies in weight of the substances with respect to the containers 25 being filled may be compensated for with the fine adjustment obtainable with the threaded rod 80 through the medium of its adjusting nut 86 and lock nut 85.

The lower extremity 73 of the measuring and dispensing chamber 71 is provided with a rectangular opening 89 for registry with an elongated discharge housing 90 that is flanged as at 91 for attachment thereto by means of a retainer frame 92. The retainer frame 92 is attached by any suitable fastening expedient such as threaded studs 93 which threadedly engage corresponding apertures provided in the bottom 73 of the measuring and dispensing cylinder 71. The lower end of the discharge housing 90 terminates, in this instance, in a substantially cylindrical end portion 94 which is somewhat larger in diameter than the width of the discharge housing to present a substantially circular cross-section.

A discharge opening 95 is provided in the lower end of the cylindrical end portion 94 of the discharge housing 90 for controlled passage of the substances therethrough by a correspondingly shaped closure plate 96 therefor. The closure plate 96 has a curvature corresponding with that of the cylindrical end portion 94. The arcuately curved closure plate 96 is disposed interiorly of the cylindrical end portion 94 and intermittently rotates relative to the discharge opening 95 to control the passage of the substances therethrough as such is extruded under the pressure of the piston 74.

As shown, the arcuate closure plate 96 (Figures 8 and 15) is provided with circular end members 97 and 98, and the latter has a crank 99 attached thereto. The crank 99 is provided with an arm 100 constituting, in this instance, a pin which projects through a slot 101 (Figure 12) provided in the extremity of the lever 102. The lever 102 is pivoted intermediate the extremities thereof as at 103 to the retainer frame 92. A bracket 104 is mounted by studs 105 and 106 to a flange 107 supported by or constituting a part of a plate 108 fixed to the substance conveyor housing bracket 64.

A cam follower wheel 109 is journaled on a pin 110 fixed to the upper extremity of the lever 102 for displacement along an irregular cam groove 111 formed in the bracket 104. It will be observed that with the vertical reciprocation and displacement of the piston 74 that is accomplished in part during the corresponding displacement of the cylinder 71, the discharge housing 90 will descend therewith so that the cam follower wheel 109 will pass through and along the irregular cam groove 111 to intermittently rotate the arcuate closure 96 of the correspondingly shaped discharge orifice 85 for operation in timed relation with and responsive to the descent of the measuring and dispensing cylinder 71. To this end, the filled dispensing cylinder 71 and its discharge

housing 90 move downwardly with the piston 74 which is relatively stationary within the cylinder 71 during the initial descent thereof which brings the discharge housing 90 and particularly its discharge orifice 95 just above and proximate to the foremost receptacle 25 on the conveyor belt 26. After the arcuate closure 96 is rotarily displaced from the discharge orifice 95 during this descent, the piston 74 is then forced downwardly in the cylinder 71 to express the contents therefrom and through the housing 90 for discharge through its orifice 95 into a receptacle 25 therebeneath, as will appear more fully hereinafter.

As shown, the indexing mechanism rod 58 extends upwardly to project through a guide plate 112 (Figure 6). The plate 112 is supported by the top end plate 77 of the measuring and dispensing cylinder 71. To this end a wing nut 113 threadedly engages a stud (not shown) that retains the guide plate 112 in horizontal extending position to confront the offset extension 56 of the bracket 46 so that the indexing rod 58 may reciprocate therebetween. A spring 114 envelops the rod 58 beneath the top guide plate 112 and it is maintained in the desired position by a collar 116 fixed to the rod extremity above the guide plate 112 which moves with the cylinder 71. As a result, the indexing rod 58 will be normally urged downwardly through the influence of the spring 114 in the path of the teeth 55 on the wheel 54 to retain the tooth wheels 58-51 against rotation responsive to the linear movement of the conveyor belt 26. Thereafter, the receptacles or containers 25 will be maintained stationary until the measuring and dispensing cylinder 71 has discharged its contents in its lowermost position and has ascended to its upper extreme position coincident with elevating the rod 58 momentarily above the teeth 55 on the wheel 54 and only for a sufficient distance to disengage the toothed wheel 54. This upper extreme position of the cylinder 71 is only retained for a moment and just long enough for the cam groove 169 that actuates the cylinder moving lever 167, to pass its high point and come to rest just past the latter's center which will return the cylinder 71 downwardly for a small distance to its initial charging position (Figure 8), thereby lifting the rod 58 up and down to disengage one tooth 55 and engage the next succeeding tooth 55 on the plate 54.

The spring 114 (Figure 5) is placed under compression as the rod 58 returns with the cylinder 71 to its extreme upward charging position (Figure 8). After the cylinder 71 is filled to a predetermined extent with the substance from the feed housing 59, the cylinder 71 descends to its lower extreme position so that the next tooth 55 of the plate 54 will be engaged by the rod 58 to again stop plates 58-51 and retain the containers or receptacles 25 against further movement or displacement with the conveyor belt 26. As a result, the filled foremost container or receptacle 25 will be released for discharge to a suitable table by the moving conveyor belt 26 while the next succeeding container or receptacle 25 has been moved to the foremost position below the discharge orifice 95 of the housing 90. It will appear, therefore, that the receptacles or containers 25 are intermittently held stationary relative to the moving conveyor belt 26 until the measuring and dispensing cylinder 71 is positioned with its discharge housing immediately above and proximate to the foremost container or receptacle 25 simultaneous with resetting the closure plate 96 to open the orifice 95 and fill the container with a meas-

ured quantity of contents extruded therethrough under pressure of the piston 74.

When the foremost container 25 is filled with the entire contents of the cylinder 71, the cylinder 5 71 and piston 74 together with the discharge housing 90 ascends to its upper limit and simultaneously permits the release of the filled receptacle or container 25 to make room for the succeeding package or container 25 to be moved to 10 the filling station in the foremost position constituting the filling station immediately below and in vertical alignment with the discharge orifice 95 under the urge of the conveyor belt 26. This 15 cycle of operation is repeated through instrumentalities that will presently be described.

Rotation of the helical worm or conveyor 60 with its axial shaft 62 responsive to the rotation of the sprocket wheel 63 that, in turn, is operated by the power source to be hereinafter described, 20 feeds the substances through the orifice 67 that is in alignment with the throat 68 communicating with the entrant orifice 72 of the measuring and dispensing cylinder 71. The passage of the substances into the cylinder 71 serves to raise 25 the piston 74 until it reaches its upper pre-set adjustable stop 79. When the cylinder 71 has been filled to this extent, the excess substances being conveyed along the worm 60, is displaced into a reserve cylinder 117 (Figures 3 and 8) that 30 constitutes the density control for the substance which is subjected to a uniform pressure.

The density of the substances would otherwise vary depending upon the pressure, the moisture content, and other factors. Variations in the 35 density of the substances would render impossible the accurate measuring and discharge of a pre-determined uniform quantity into the receptacles or containers 25. The density control cylinder 117 is, in this instance, formed integral with the 40 feeding housing support bracket 64 and extends rearwardly in a direction opposite to the primary discharge orifice 67.

The feeding housing 59 is provided with an orifice 118 that communicates with the density 45 control cylinder 117 fitted with a piston 119 that is anchored to a rod 120. The piston rod 120 is reciprocally mounted through a bore 121 of a cylinder cap 122 that serves to close the density control cylinder 117.

50 It will be observed that the cross-sectional area of the cylinder housing 117 together with its commensurate entrant orifice 118 is substantially larger than the primary discharge orifice 67 disposed diametrically opposite thereto. Thus the 55 total substance pressure built up within the cylinder housing 117 together with the pressure of the excess substances in the density control cylinder 117 is transmitted to the piston 119 that displaces the piston rod through the cylinder cap 122 against the urge of a coil spring 123 which 60 envelops the externally projecting portion of the piston rod 120. The piston rod 120 projects through an axially bored collar 124 that is free on the piston rod 120 and normally urged by the 65 spring 123 in the direction of another collar 124' fixed to the rod 120 for displacement therewith relative to the cylinder end cap 122. The spring 123 envelopes the rod 120 between the free collar 124 and a stop 125 axially bored as at 126 to serve 70 as a spaced piston rod guide in conjunction with the cylinder cap 122. The spring 123 is compressed during the outward movement of the piston 119 and rod 120, and serves to return these parts to initial position after the contents of the 75 cylinder 59 is sufficiently discharged to release

the pressure therein and displace any excess substance from the cylinder housing 117.

Suitable means 127 serving as a guard for the piston rod 120 and its spring 123 is anchored between the cylinder head 122 and the end guide stop 125. The axially bored rod affixed collar 124' has an upstanding plate 128 provided with a horizontally projecting stud 129 provided on its extremity with threaded lock nuts 130. A coil spring 131 envelops the stud 129 to bear against the vertical portion 132 of a right angular trip 133. The vertical trip arm 132 is suitably apertured to enable tilting relative to the stud 129 so that the urge of the spring 131 will cause the trip 133 to pivot in a clockwise direction about a pin 134 that pivotally connects the right angular trip 133 to the vertical plate 128.

A horizontal arm 135 of the trip member 133 is provided with a series of upstanding serrations or teeth 136, in this instance three, that cooperates with a pawl 137 that depends from the horizontal rod 137' anchored in the lower extremity of a vertical rod 138 to impart rotary movement thereto. A series of teeth 136 are provided to insure that one or the other thereof will engage the pawl 137, since the latter may slip over the first tooth 136 in the event the trip member 133 is not in its extreme clockwise position (viewed from Figure 8). While one tooth 136 would suffice for most operations, yet it is best to provide a series of teeth as a safety feature to insure dependable engagement under all conditions of operation. The vertical rod 138 is rotatively journaled in a tube or guide sleeve 139 which is integrally or otherwise attached to a bracket plate 140 to enable the fixed attachment thereof to the top plate 20 of the superposed frame 17 (Figure 8). The tiltable right-angular trip 133 permits the teeth 136 to ride past the pawl 137 on the return movement of the plunger rod 120.

The vertical rod 138 terminates upwardly in a trip 141 having an engaging stud 141' projecting radially through a hub 142 thereof. The trip 141 and its hub 142 are oscillatably mounted relative to the stationary guide sleeve or tube 139 through the medium of a coil spring 142' interposed therebetween to rotatively urge the trip 141 with its hub 142 in a clockwise direction (viewed from Figure 10). The trip 141 and its hub 142 has an extension 143 which is oscillatably limited in its movement by confronting adjustable studs 144—144' that are mounted in confronting upstanding arms 145 and 145' (Figure 10) anchored as at 146 to the upper extremity of the vertical tube or guide sleeve 139.

The studs 144—144' enable the rotary adjustment of the trip 141 on the top extremity of the rod 138 for limiting actuation of the trip lever extremity 147 to swing into and out of engagement with a trunnion 148 carried by a clutch element 149. The clutch element 149 is pivotally mounted as at 150 to the external housing 151 of a peripherally toothed clutch element 152. The peripheral toothed clutch member 152 is attached through its hub sleeve to a shaft 153 which is rotatively driven by any suitable power instrumentalities to be hereinafter described.

As shown, the pivotal clutch element 149 has a pawl 154 that meshes with the peripheral teeth on the clutch element 152 to impart corresponding rotary movement to the clutch housing 151. A spring 155 cooperates with a pin 156 formed on the other extremity 158 of the clutch element 149 for imparting a counter-clockwise urge thereto (viewed from Figure 4). This is accomplished by

lodging the spring 155 in an annular aperture 159 formed on the external clutch housing 151. It will be apparent, therefore, that the counter-clockwise rotation of the clutch element 152 will impart corresponding directional rotation to the clutch housing 151 for one revolution whenever the trip 141 is rotarily displaced responsive to corresponding movement of the pawl 137 (Figure 9). This movement is translated through the rod 138 which is actuated when the teeth or serrations 136 on the trip 133 are linearly displaced with the piston rod 120 (Figure 8). This occurs whenever the conveyor 60 has filled the cylinder 71 to its desired extent and displaces the piston 119 with the excess substances to impart corresponding displacement to the trip 133.

In short, the lever arm 168 can be freely oscillated when the cylinder 71 is empty which occurs at the end of each cycle of operations, since the clutch shown in Figure 4 is a one-turn type well known in its use on punch press machines and the like. This type of clutch is disengaged when all the instrumentalities have returned to their initial position in readiness for the next cycle of operation. The pawl 154 is fixed to the arm 149 which has a lug 148 in the path of the trip 141, the latter having its nose or pointed extremity 147 normally disposed in the path of the lug 148 by virtue of the spring 142'. As the shaft 153 rotates with the clutch element 152 in a counter-clockwise direction (viewed from Figure 4), the engagement of the pawl 154 with any one of the ratchet teeth on the clutch element 152 responsive to the urge of the spring 155 (Figure 4), the clutch housing 151 will rotate with the clutch element 152 for one full revolution. Because the nose 147 of the trip 141 is again displaced by the spring 142' in the path of the lug 148 before the clutch housing 151 rotates one revolution, the pawl 154 is disengaged from the clutch element 152 and the clutch housing 151 with its tubular shaft 162 is brought to an abrupt stop as the lug 148 hits the shoulder 141' on the trip 141.

Thereafter, it is necessary to rotarily displace the trip 141 about its mounting shaft 138 against the urge of the spring 142', thereby permitting the pawl 154 to become reengaged with the ratchet teeth 152 to repeat the one-turn revolution of the shaft 162. This is accomplished by the excess chamber 117 (Figure 8) being filled sufficiently for the trip 133 to be moved to the right with the collar 124 and the rod 120 (Figure 8) so that the first tooth 136 thereon will displace the pawl 137, thereby rotating the shaft 138 to effect the removal of the trip 141 from the path of the pawl lug 148. Thereupon, the clutch rotates past the trip 141 which immediately returns to its initial position under the influence of the spring 142', this occurring before the lug 148 again reaches the extremity 147 of the trip 141. After the contents of the cylinder 71 has been emptied, the pressure of the substance in the feeding housing 59 is less than the force of compression in the spring 123 which returns the piston 119 to empty the excess cylinder 117.

This insures the dependable operation of the instrumentalities that are driven by the shaft 153. The shaft 153 is journaled in bearing brackets 160 and 161 mounted to the top 20 of the superimposed frame 17 (Figure 1) to serve as a support for the shaft 153 and the operating instrumentalities connected therewith. As shown, the external clutch housing 151 has a tubular shaft 162 extending therefrom to enable the shaft 153 that projects therethrough (Figure 7) to sup-

port instrumentalities that are to be rotated with the shaft 162. The cams 163 and 164 are mounted on the tubular shaft 162 to cooperate with cam follower rollers 165 and 166 rotatively mounted on lever cranks 167 and 168, respectively.

It is to be noted that the cam follower roller 165 rides in a lateral cam groove 169 provided in the lateral wall of the cam 163. The crank levers 167 and 168 terminate in tubular bearings 170 and 171 that receive the shaft 172 therethrough for mounting in bearing brackets 173 and 174 (Figure 1). The bearing brackets 173 and 174 are attached to the top plate 20 of the super frame 17. These bearing brackets 173-174 carry a rod 172 which pivotally supports the levers 167-168 for timed oscillatory movement responsive to the rotation of the cams 163-164. It will be observed that the crank lever 167 is pivotally mounted at its forward extremity to a pin 175 carried by a depending link 176 having a furcated extremity 177 provided for that purpose.

The lower extremity of the depending link 176 is pivoted as at 178 to a bracket 179 integrally or otherwise attached to the top closure plate 71 of the measuring and dispensing cylinder 71 to effect the ascent and descent thereof in the confronting groove 70'. The lever crank 168, on the other hand, has a rounded extremity 180 which is shaped to project into and engage the slotted shoulder 181 provided on the piston rod 75 to effect the ascent and descent thereof in timed relation with the displacement of cylinder 71. To this end, the piston rod 75 is reciprocally guided in the bearing 182 fixed to the top extremity of a substantially U-shaped guard housing 183 that is anchored to a shoulder 184 integrally or otherwise formed on the cylinder top closure plate 71, the guard 183 being held stationary relative to the cylinder 71 to preclude any possible injury to the attendant who may be called upon to manipulate the adjusting nuts 85-86.

In order to release the clutch elements 149-152 after the cylinder 71 has been actuated to its lowermost position and recedes to its filling position just below the maximum ascent thereof and constituting the initial position thereof, the crank lever 167 is provided with an adjustable link rod 185 which is pivotally connected thereto as at 186. The link rod 185 threadedly engages the complementary tubular member 187 that is pivotally connected to a pin 188 which extends through spaced furcations 189 provided on the trip 133.

It should be noted that the pin 188 projects through a stub rod 185' that freely telescopes within the lower end of the sleeve 187 for yieldable connection thereto through the medium of a tension coil spring 189'. The tension spring 189' is confined in the sleeve 187 with the lower end of the spring 189' anchored to the stub rod 185' and the upper end thereof fixed to a cross-pin 188' which extends diametrically through the sleeve 187 below the bottom end of the rod 185 (Figure 8). When the lever 167 pivots in a clockwise direction (viewed from Figure 8) to elevate the cylinder 71 and the latter is momentarily lifted above its initial starting position to disengage the indexing rod 58 from the toothed wheel 54, the spring 189' will yield to impart tension therein and thereafter assume its normal length upon the return of the cylinder 71 to its initial filling or charging position (Figure 8) where it is held until filled with a predetermined volume of substance.

The return or counterclockwise movement of

the lever 167 is interrupted just as the high point of the cam groove 169 traverses beyond the cam follower 165. This occurs coincident with the arrival of and engagement by the trip lever trunnion 148 with the trip 141-147 to disengage the clutch housing 151 from the clutch element 152 to bring the cylinder 71 to an abrupt stop. The clutch trip 141-147 is in this tripping position shortly after the filled or charged cylinder 71 starts to move downwardly responsive to the filling of the excess density control cylinder 17 which again rotates the trip 141-147 from the path of the trip lever trunnion 148. Thereupon, the clutch element 152 and clutch housing 151 are engaged for one full revolution. This downward movement of the fully charged cylinder 71 responsive to the lever 167 that is displaced by the rotation of the cam 169 serves to pivotally displace the trip arm 135 in a counterclockwise direction (viewed from Figure 8) between the initial upward filling position of the cylinder 71 and the lowermost discharge position thereof to free the pawl 137 from the serrations or teeth 136 on the trip arm 135 thereby permitting the return of the clutch trip 141 to its initial position responsive to the urge of the spring 142' (Figure 4), and the trip 141 in this position effects the disengagement of the clutch element 149 from the clutch element 152. This completes a cycle 20 of operation for filling a single container 25, and another cycle starts immediately in that the substance feed worm 62 rotates continuously to again fill the cylinder 71 and the density control cylinder 117.

No further operation of the instrumentalities is, however, rendered possible until the cylinder 71 has again been filled to its pre-set volume and the excess substance is forced into the density control cylinder 117 to displace the piston 119 to the right (viewed from Figure 8) to correspondingly displace the trip arm 135 with its serrated teeth 136 to again actuate the clutch element 149 through the medium of the pawl 137 disposed in the path of the trip teeth 136. This will repeat the operation for filling another receptacle or container 25 in an automatic cycle of operations until all of the substances have been fed through the housing 59 into the cylinder 71 for filling the receptacles or containers 25.

The excess substance that enters the density control cylinder 117 is returned to the feeding housing 59 through the urge of the spring 123. This occurs when the cylinder 71 is empty or partially unfilled while substances are being supplied thereto from the feeding housing 59, and during this time the pressure in the feeding housing 59 is less than that exerted by the spring 123. The clutch shaft 163 and the feed worm 62 are all operated from a common source of power such as an electric motor 190 that is attached to a speed reducer 191 having its housing formed integral with a bracket 192. The bracket 192 is fixed to the top plate 20 of the super frame 17 to rotate a shaft 193 responsive to the energization of the electric motor 190. The speed reducer shaft 193 has a pair of sprockets 194 and 195 fixed thereon for meshing engagement with sprocket chains 196 and 197, respectively.

The sprocket chain 196 meshes with a sprocket wheel 198 fixed to the shaft 30 (Figure 2) that rotates the conveyor drum or pulley 28 to impart linear movement to the endless conveyor belt 26. The sprocket chain 197 meshes with a sprocket wheel 199 carried by a sleeve 200 integrally

formed with the clutch element 152 (Figures 4, 7, and 10). Consequently, the clutch element 152 will be continuously rotated at constant speed relative to the clutch element 149 pivotally mounted to the clutch housing 151. The stub shaft 153 which rotates with the clutch sleeve 200, is provided with a sprocket wheel 201 (Figures 2 and 7) fixed thereon to mesh with a sprocket chain 202 that lies over an idler pulley 203 mounted on the super frame 17.

The sprocket chain 202 extends beyond the idler sprocket 203 to mesh with a sprocket wheel 63 fixed to the extremity of the conveyor shaft 62 to impart constant rotation thereto for feeding the substance from the source of supply as above described. The clutch element 152 with its sleeve 200 is fixed to the stub shaft 153 for rotation therewith. The sprocket 199 has its hub fixed to the clutch element sleeve 200 while the clutch housing 151 has its sleeve 162 journaled on the stub shaft 153 to rotate relative thereto or therewith through the clutch element 152 and the housing 151 when interengaged by the clutching member 149. The cams 164 and 169 are fixed to the clutch housing sleeve 162 to rotate therewith through the operation of the clutching member 149 in connecting the stub shaft 153 therewith. It will be observed, therefore, that all of the instrumentalities are operatively connected for actuation responsive to the rotation of the electric motor 190.

In order to maintain the substances at the proper temperature, a cylinder jacket 205 envelops the substance feeding housing 59 to present a chamber 206 that receives a temperature controlling fluid such as hot water. That portion of the feeding housing 59 that is confined by the supporting bracket 64 is also maintained at the proper temperature by means of a jacket 207 (Figure 13) which is disposed therearound to provide a chamber 208. A similar jacket 209 is provided around the major portion of the measuring and dispensing cylinder 71 to provide a water chamber 210.

The chambers 206, 208 and 210 are interconnected through hoses 211 and 212 (Figures 1 and 13) that communicate with tubular nipples 213-214 and 215-216 provided in the jackets 205, 207 and 209 to communicate with the chambers 206, 208 and 210. A tubular nipple 217 projects from the lower part of chamber 208 to enable connection of the flexible hose 218 to the discharge port of a circulating pump 219 mounted on the top plate 20 of the super frame 17 (Figure 1). Another hose 220 extends from the upper nipple 221 of chamber 210 to any convenient drain such as a receiver (not shown) for recirculation through another hose 222 connected to the intake port of the circulating pump 219 for communication with any source of hot water such as a supply heater tank (not shown). The pump 219 has a sprocket 223 rotatively connected to the sprocket chain 197 to impart rotation thereto so that continuous pumping of the water is effected through the tempering chambers 206, 208 and 210 to maintain the substances at the proper temperature. Should the character of the substances as well as the atmospheric conditions require a decrease in temperature, then cold water could be substituted for hot water to procure the desired tempering control.

In operation, the motor 190 continuously drives the conveyor feed screw 60 through the medium of the shaft 62 and its sprocket wheel 63 to con-

vey the substances such as plastic cheese through the feeding housing 59 from a suitable source of supply. The sprocket 63 is driven by a chain 202 that meshes with a sprocket wheel 201 which is continuously driven by the clutch shaft 153. The clutch shaft 153 is in turn driven by the sprocket 199 fixed to the sleeve 200 constituting part of the clutch element 152 fixed to the shaft 153. A chain 197 connects the sprocket 199 with the sprocket 195 carried by the reduction gear shaft 193. The reduction gear shaft 193 is driven by the motor 190 through a train of internal gears (not shown). The substances will, thereupon, pass through the rectangular discharge orifices 67-68-72 to elevate the piston 74 within the measuring and dispensing cylinder 71 until it reaches the limit of the stop 79. It should be assumed that the stop 79 is preset for any selected quantity of plastic substance that is to constitute a single charge for the containers or boxes 25.

The piston rod 75 is operatively connected to the lever arm 168 which, in turn, is pivoted to the shaft 172 mounted in the bearing bracket 174. The lever arm 168 is free to oscillate responsive to the movement of the piston 74 so long as the actuator cam 164 (Figures 7 and 17) is removed from the path thereof in its initial stationary position with the lobe of the cam 164 substantially above the mounting shaft 162 (Figure 17). This is determined by the tubular shaft 162 which is clutch operated (Figure 4) after the cylinder 71 is filled with the substance to be packaged and the excess cylinder 117 is partially charged to move the trip arm 133 with its teeth 136 against the pawl 137. This rotates the shaft 138 (Figures 4 and 9) to rotatively displace the trip 141 from the path of the pawl 154 and its lug 148, thereby allowing the pawl 154 to engage the ratchet teeth on the clutch element 152 that continuously rotates with the shaft 153.

Thereupon, the clutch housing 151 with its tubular shaft 162 and the cams 164-169 are rotated one revolution to actuate the levers 168 and 167 through the downward phase of a complete oscillation according to the shape and timing position of the cams 164 and 169 on the shaft 162. It should be noted that as the lever arm 167 reaches its extreme downward displacement with the cylinder 71 in its lowest position, the rod 185-187 is only slightly displaced downwardly owing to its proximity to the lever pivot 172 to pivotally depress the angle trip 133 in a counterclockwise direction (viewed from Figure 8) so that the teeth 138 would be clear of the pawl 137 and permit the latter to easily return to its initial position under the influence of the spring 142' (Figure 4).

When the cylinder 71 has been filled through the rotation of the conveyor feed screw 60, the excess causes the density control piston 119 to recede within the cylinder 117 against the urge of the spring 123. Thereupon, the upstanding plate 128 is moved therewith to correspondingly displace the trip arm 135 with its teeth 136 in the path of the pawl 137. This displacement causes the partial rotation of the detent 131 to correspondingly turn the trip 141 (Figure 4) to release the clutch element 149 so that the pawl 154 thereon will engage the teeth of the clutch element 152 responsive to the urge of the spring 155. This will cause the rotation of the tubular clutch shaft 162 (Figure 7) so that cams 163 and 164 will displace the levers 167 and 168.

Thereupon, the piston 74 and measuring cylinder 71 are displaced downwardly so that the dispensing housing 90 and its cylindrical extremity 94 will closely approach the open top of the container 25 disposed at the filling station. During the downward movement of the dispensing housing 90, the lever 102 is displaced therewith so that the cam follower 109 will follow the cam groove 111 to rotate the dispenser closure 96 in timed relation with the piston 74 so that the container 25 at the filling station will be charged with a predetermined quantity of substances.

The containers 25 are lined with suitable sheet material depending upon the dictates of commercial practice and at the moment that the container 25 disposed at the filling station is completely charged with the substances, the measuring cylinder 71 ascends upwardly to momentarily elevate the indexing rod 58 (Figure 6) and permit the ratchet wheel 54 to rotate with the cylinder 49 in frictional contact with the endless belt conveyor 26. The endless belt conveyor 26 is continually driven and when the indexing rod 58 is in engagement with the ratchet wheel 54, the belt 26 slips over the periphery of the drum 49. When the trip rod 58 is momentarily elevated as described herein, the cylindrical drum 49 will rotate to permit the container 25 at the filling station to be delivered to its desired destination responsive to the endless conveyor belt 26 in that the teeth 52-53 of the end plates 50-51 will rotate with the drum 49 to permit the delivery of the filled container 25.

Thereupon, the succeeding container 25 is carried by the endless conveyor belt 26 to the filling station with the next succeeding teeth 52-53 on the drum end plates 50-51 again disposed in the path of the succeeding container 25 to maintain such in registry with the dispensing housing 90 at the filling station. As the container 25 at the filling station is filled, the timed actuation of the various instrumentalities described permits the ascent of the piston 74 so that the excess substances conveyed into the control cylinder 117 is discharged therefrom into the feeding housing 59 by the piston 119 which is actuated under the urge of the spring 123, thereby returning the parts to their initial position in readiness for a repeat cycle of operation in that the clutch trip spring 142 will return the trip 141 to its initial position to disengage the clutch housing 151 with its pawl 154 from the clutch element 152 so that the actuating levers 167-168 are rendered inactive while the measuring and dispensing cylinder 71 is again being filled.

More specifically, the cylinder 71 is initially at its charging position (Figure 8) when the clutch housing 151 has been disengaged from the clutch element 152 and this charging position of the cylinder 71 is maintained until filled with the substances forced therein from the feed housing 59 by the continuously rotating worm 60. The charging of the cylinder 71 serves to elevate the piston 74 therein until it reaches the adjustable limit stop 79 which is pre-set to allow a predetermined quantity of substances to be introduced in the cylinder 71 commensurate with the size of the containers 25 to be filled. The piston rod 75 is fixed to and moves upwardly with the cylinder piston 74.

The lever 168 is raised with the piston rod 75 in that the cam follower 166 thereon is out of engagement with the cam 164 which has its high point disposed on the opposite side of its mount-

ing shaft 162 (Figure 7) when the clutch housing 151 is disengaged from the clutch element 152. When the cylinder 71 is filled with the substance supplied thereto by the worm 60 in the housing 59, there can be no further introduction of substances therein. Continued rotation of the feed worm 60 effects the feeding of the substances into the control cylinder or excess substance chamber 117 to displace the piston 119 with its rod 120 toward the right (viewed from Figure 8). The bracket supporting collar 124' fixed to the piston rod 120 will be correspondingly displaced with the bracket 133 to move the spring sustaining collar 124 therewith and compress the spring 123. 15 When sufficient excess substances have been introduced into the control cylinder 117 to displace the piston rod 120 a distance sufficient to carry the collar 124' and its attached bracket 133 so that its teeth 136 engage the pawl 137, the vertical shaft 138 is rotarily displaced to move the trip 141 with its pointed extremity 141 from the path of the clutch pawl lug 148, thereby disengaging the trip 141 therefrom and permitting the clutch spring 155 to effect engagement between the pawl 154 and the teeth of the clutch element 152 (Figure 4) that continuously rotates with the shaft 153. Consequently, the clutch housing 151 will rotate with the clutch element 152 to correspondingly rotate the sleeve shaft 162 (Figure 2) and cause the cams 163-164 to rotate therewith.

The cam 163 has its cam groove 169 in engagement with the cam follower 165 to depress the lever 167 (Figure 8), thereby lowering the cylinder 71 with its dispensing housing 90 to the foremost container 25 which is at the filling station. This downward movement of the cylinder 71 causes the cam follower 109 on the discharge closure plate operating lever 102 (Figure 12), to follow the irregular cam groove 111 formed in the bracket 104. The passage of the cam follower 109 along the cam groove 111 effects the rotation of the arcuate closure plate 106 to assume a position out of registry with the discharge orifice 95 at which time the cam 164 effects engagement with the cam follower 168 on the lever 168 to depress the cylinder piston 74. This displaces the piston 74 within the cylinder 71 to extrude the substances through the discharge orifice 95 for deposit in the foremost container 25 supported by the conveyor belt 26 at the filling station.

With the discharge of the substances from the cylinder 71, the clutch housing shaft 162 continues to rotate with the cam 163-164 to actuate the levers 167-168 so that the cylinder 71 and its piston 74 are returned to their initial extreme upward position. In the course of the upward displacement of the cylinder 71, however, the cam 163 effects the momentary elevation thereof slightly above its initial upward charging position to impart corresponding movement to the indexing rod 58 which disengages the engaged tooth 55 and instantly returns to engage the next succeeding tooth 55 on the indexing plate 54. This elevated displacement of the cylinder 71 and rod 58 for an instant above its initial starting position is effected by the cam 163 whose cam groove 169 moves past its high point center for a short distance and comes to rest simultaneous with the disengagement of the clutch housing pawl 154 from the clutch element 152.

The disengagement of the pawl 154 from the clutch element 152 is effected by the return of the trip 141 disposed in the path of the pawl

lug 148 (Figure 4) through the influence of the spring 142'. The spring 142' is free to effect the return of the trip 141 with its shaft 138 owing to the depression of the bracket arm 135 in a counter-clockwise direction (viewed from Figure 8) against the urge of the contracting spring 131. This occurs while the lever 167 moves downwardly to effect the descent of the cylinder 71 and also to a lesser extent downwardly displaces the rod 185 that is operatively connected to the bracket 133. Thus, the counter-clockwise depression of the bracket 133 (Figure 8) occurs responsive to the rod 185 after the clutch housing pawl 154 with its lug 148 rotates with the clutch element 152 beyond the trip 141, thereby again placing the latter in the path of the pawl 154 before it and the clutch housing 151 completes a full revolution.

Consequently, the clutch housing 151 with its tubular shaft or sleeve 162 that carries the cams 163—164 therewith, can rotate only for a single revolution which actuates the instrumentalities and effects their return to their initial position to start the next cycle of operation after the cylinder 71 is filled and the control cylinder or the excess substance chamber 111 is again charged to provide for the connection between the clutch housing 151 and the clutch element 152. All during this time the shaft 153 continuously rotates so that the worm 60 in the feed housing 59 will always be ready to feed substances first to the cylinder 71 and thereafter to the control cylinder or excess substance chamber 111. The power source comprising, in this instance, the electric motor 190, is in continuous operation except when its master control switch (not shown) is shut-off to bring all instrumentalities to a stop.

It will appear, therefore, that a very precise, accurate and dependable container filling machine has been provided that is automatic and is sufficiently flexible in adjustment so that a great variety of weights in differently sized containers 25 may be packaged. Various changes may be made in the embodiment of the invention herein specifically described without departing from the invention or sacrificing any of the advantages or features thereof, and nothing herein shall be construed as limitations of the invention, its concept or structural embodiment as to the whole or any part thereof except as defined in the appended claims.

We claim:

1. In a container filling machine, the combination with a measuring chamber, of means for feeding substances into said measuring chamber, a substance excess control chamber communicating with said measuring chamber, means for discharging the substances from said measuring chamber, and means responsive to filling said control chamber for effecting the operation of said measuring chamber discharging means.

2. In a container filling machine, the combination with a measuring chamber, of means for feeding substances into said measuring chamber, means for discharging the substances from said chamber, an excess substance chamber communicating with said feeding means, and means in said excess substance chamber responsive to the excess substances introduced by said feeding means after filling said measuring chamber for controlling the operation of said chamber discharging means.

3. In a container filling machine, the combination with an adjustable measuring chamber, of

means for feeding substances into said adjustable measuring chamber, piston means in said chamber for discharging the substances from said measuring chamber, an excess substance chamber communicating with said feeding means, and means in said excess substance chamber responsive to excess substances introduced by said feeding means after filling said measuring chamber for controlling the operation of said chamber discharging means.

4. In a container filling machine, the combination with a measuring chamber, of means for feeding substances into said measuring chamber, means for discharging the substances from said chamber, means for lowering said chamber to the container to be filled during the operation of said discharging means, and means responsive to filling said chamber for controlling the operation of said chamber lowering and discharging means.

5. In a container filling machine, the combination with a measuring chamber, of means for feeding substances into said measuring chamber, means for discharging the substances from said chamber, a discharge housing extending from and communicating with said measuring chamber, means for lowering said chamber to the container to be filled during the operation of said discharging means, and means responsive to filling said chamber for controlling the operation of said chamber lowering and discharging means.

6. In a container filling machine, the combination with a measuring chamber, of means for feeding substances into said measuring chamber, means for discharging the substances from said chamber, a discharge housing extending from and communicating with said measuring chamber, means for lowering said chamber and discharge housing proximate to the container to be filled during the operation of said discharging means, and means responsive to filling said chamber for controlling the operation of said chamber lowering and discharging means.

7. In a container filling machine, the combination with a measuring chamber, of means for feeding substances into said measuring chamber, means for discharging the substances from said chamber, a discharge housing extending from and communicating with said measuring chamber, means for lowering said chamber and discharge housing proximate to the container to be filled during the operation of said discharging means, means responsive to filling said chamber for controlling the operation of said chamber lowering and discharging means, and a control valve operatively connected to the lower open end of said discharge housing.

8. In a container filling machine, the combination with a measuring chamber, of means for feeding substances into said measuring chamber, means for discharging the substances from said chamber, a discharge housing extending from and communicating with said measuring chamber, means for lowering said chamber and discharge housing proximate to the container to be filled during the operation of said discharging means, means responsive to filling said chamber for controlling the operation of said chamber lowering and discharging means, a control valve operatively connected to the lower open end of said discharge housing, and means for opening said control valve when said normally closed discharge housing approaches the lower end of its travel proximate to the container to be filled.

9. In a container filling machine, the combination with a measuring chamber, of means for

feeding substances into said measuring chamber, means for discharging the substances from said chamber, a discharge housing extending from and communicating with said measuring chamber, means for lowering said chamber and discharge housing proximate to the container to be filled during the operation of said discharging means, means responsive to filling said chamber for controlling the operation of said chamber lowering and discharging means, a control valve operatively connected to the lower open end of said discharge housing, and cam means responsive to the descent of said measuring chamber and discharge housing for opening said control valve when said normally closed discharge housing approaches the lower end of its travel proximate to the container to be filled.

10. In a container filling machine, the combination with a measuring chamber, of means for feeding substances into said measuring chamber, means for discharging the substances from said chamber, a discharge housing extending from and communicating with said measuring chamber, means for lowering said chamber and discharge housing proximate to the container to be filled during the operation of said discharging means, means for receiving the excess substances responsive to filling said chamber for controlling the operation of said chamber lowering and discharging means, a control valve operatively connected to the lower open end of said discharge housing, and cam means responsive to the descent of said measuring chamber and discharge housing for opening said control valve when said normally closed discharge housing approaches the lower end of its travel proximate to the container to be filled.

11. In a container filling machine, the combination with an adjustable measuring chamber, of means for feeding substances into said adjustable measuring chamber, piston means in said chamber for discharging the substances from said chamber, a discharge housing extending from and communicating with said measuring chamber, means for lowering said chamber and discharge housing proximate to the container to be filled during the operation of said discharging means, means for receiving the excess substances responsive to filling said chamber for controlling the operation of said chamber lowering and discharging means, a control valve operatively connected to the lower open end of said discharge housing, and cam means responsive to the descent of said measuring chamber and discharge housing for opening said control valve when said normally closed discharge housing approaches the lower end of its travel proximate to the container to be filled.

12. In a container filling machine, the combination with an adjustable measuring chamber, of means for feeding substances into said adjustable measuring chamber, piston means in said chamber for discharging the substances from said chamber, a discharge housing extending from and communicating with said measuring chamber, means for lowering said chamber and discharge housing proximate to the container to be filled during the operation of said discharging means, pressure means communicating with said feeding means for receiving the excess substances responsive to filling said chamber for controlling the operation of said chamber lowering and discharging means, a control valve operatively connected to the lower open end of said discharge housing, and cam means responsive

to the descent of said measuring chamber and discharge housing for opening said control valve when said normally closed discharge housing approaches the lower end of its travel proximate to the container to be filled.

13. In a container filling machine, the combination with an adjustable measuring chamber, of means for feeding substances into said adjustable measuring chamber, piston means in said chamber for discharging the substances from said chamber, a discharge housing extending from and communicating with said measuring chamber, means for lowering said chamber and discharge housing proximate to the container to be filled during the operation of said discharging means, spring impelled pressure piston means communicating with said feeding means for receiving the excess substances responsive to filling said chamber for controlling the operation of said chamber lowering and discharging means, a control valve operatively connected to the lower open end of said discharge housing, and cam means responsive to the descent of said measuring chamber and discharge housing for opening said control valve when said normally closed discharge housing approaches the lower end of its travel proximate to the container to be filled.

14. In a container filling machine, the combination with a measuring chamber, of means for feeding substances into said measuring chamber, a piston in said measuring chamber, a piston rod for guiding said piston, an adjustable stop in said chamber to limit the displacement of said piston responsive to feeding substances into said measuring chamber, a supplemental chamber communicating with said feeding means for receiving the excess substance after said piston has reached its displacement controlled by said adjustable stop, and means for displacing said piston and measuring chamber to discharge the substances into a container disposed in the path thereof.

15. In a container filling machine, the combination with a measuring chamber, of means for feeding substances into said measuring chamber, a piston in said measuring chamber, a piston rod for guiding said piston, an adjustable stop in said chamber to limit the displacement of said piston responsive to feeding substances into said measuring chamber, a supplemental chamber communicating with said feeding means for receiving the excess substance after said piston has reached its displacement controlled by said adjustable stop, means for displacing said piston and measuring chamber to discharge the substances into a container disposed in the path thereof, and a discharge control valve operatively connected to said measuring chamber.

16. In a container filling machine, the combination with a measuring chamber, of means for feeding substances into said measuring chamber, a piston in said measuring chamber, a piston rod for guiding said piston, an adjustable stop in said chamber to limit the displacement of said piston responsive to feeding substances into said measuring chamber, a supplemental chamber communicating with said feeding means for receiving the excess substance after said piston has reached its displacement controlled by said adjustable stop, means for displacing said piston
60 and measuring chamber to discharge the substances into a container disposed in the path thereof, a discharge control valve operatively connected to said measuring chamber, and means responsive to the displacement of said measuring chamber to operate said control valve.

17. In a container filling machine, the combination with a measuring chamber, of means for feeding substances into said measuring chamber, a piston in said measuring chamber, a piston rod for guiding said piston, an adjustable stop in said chamber to limit the displacement of said piston responsive to feeding substances into said measuring chamber, a supplemental chamber communicating with said feeding means for receiving the excess substance after said piston has reached its displacement controlled by said adjustable stop, means for displacing said piston and measuring chamber to discharge the substances into a container disposed in the path thereof, a discharge control valve operatively connected to said measuring chamber, means responsive to the displacement of said measuring chamber to operate said control valve, and means responsive to filling said measuring chamber for controlling the operation of said piston and chamber displacing means.

18. In a container filling machine, the combination with a measuring chamber, of means for feeding substances into said measuring chamber, a piston in said measuring chamber, a piston rod for guiding said piston, an adjustable stop in said chamber to limit the displacement of said piston responsive to feeding substances into said measuring chamber, a supplemental chamber communicating with said feeding means for receiving the excess substance after said piston has reached its displacement controlled by said adjustable stop, means for displacing said piston and measuring chamber to discharge the substances into a container disposed in the path thereof, a discharge control valve operatively connected to said measuring chamber, means responsive to the displacement of said measuring chamber to operate

said control valve, and means responsive to the excess substance in said supplemental chamber for controlling the operation of said piston and chamber displacing means.

19. In a container filling machine, the combination with a measuring chamber, of a piston in said measuring chamber for limiting the introduction into and effecting the discharge of substances from said measuring chamber, adjustable means associated with said measuring chamber to serve as a stop for said piston in admitting substances into said measuring chamber, a supplemental chamber communicating with said feeding means for receiving the excess substance after said piston has reached its displacement controlled by said adjustable stop, and means responsive to filling of said measuring chamber for operating said piston to discharge the substances from said measuring chamber.

20. In a container filling machine, the combination with a measuring chamber, of a piston in said measuring chamber for limiting the introduction into and effecting the discharge of substances from said measuring chamber, adjustable means associated with said measuring chamber to serve as a stop for said piston in admitting substances into said measuring chamber, another chamber communicating with said measuring chamber for receiving the excess substance after said measuring chamber is filled, and means responsive to filling of said excess substance chamber for operating said piston to discharge the substances from said measuring chamber.
